No. 813,146.

PATENTED FEB. 20, 1906.

J. W. FULLER, JR.

MODE OF PRODUCING SELF LUBRICATING CAR WHEELS.

APPLICATION FILED SEPT. 16, 1905.

UNITED STATES PATENT OFFICE.

JAMES W. FULLER, JR., OF CATASAUQUA, PENNSYLVANIA.

MODE OF PRODUCING SELF-LUBRICATING CAR-WHEELS.

No. 813,146.

Specification of Letters Patent.

Patented Feb. 20, 1906.

Application filed September 16, 1905. Serial No. 278,823.

To all whom it may concern:

Be it known that I, JAMES W. FULLER, Jr., a citizen of the United States, residing at Cata-
sauqua, in the county of Lehigh and State
5 of Pennsylvania, have invented certain new
and useful Improvements in the Mode of
Producing Self-Lubricating Car-Wheels, of
which the following is a specification.

My invention has relation to a mode of
10 forming self-lubricating car-wheels; and in
such connection it relates more particularly
to the mode of casting a chambered integral
hub portion and of establishing a connection
between certain separated chambers thereof.

15 The principal objects of my invention are,
first, to form a self-lubricating car-wheel with
an integral (*i. e.*, an undivided) hub portion
having chambers cast therein to receive a lu-
bricant and an axle; second, to connect cer-
20 tain of said chambers with each other by
forming openings in certain of the walls there-
of after the wheel has been cast, so as to per-
mit of the flow of a lubricant from a certain
chamber to another certain chamber thereof,
25 which conducts the same to a chamber adapt-
ed to receive an axle, and, third, to close the
openings formed in one of the walls to render
a certain chamber adaptable for the recep-
30 tion of a lubricant and to permit the same
by the openings formed in another wall to
pass from the receiving-chamber into a dis-
tributing-chamber, which conducts the lu-
bricant to an axle terminating in a third
35 chamber formed in the hub.

35 The nature and scope of my invention will
be more fully understood from the following
description, taken in connection with the ac-
companying drawings, forming part hereof,
in which—

40 Figure 1 is a vertical sectional view of a
self-lubricating car-wheel, illustrating the
chambered hub portion after the casting of
the wheel embodying the features of my in-
vention. Fig. 2 is a detail view illustrating
45 in section the formation of openings formed
in contiguous vertical walls of the hub por-
tion to connect certain of the chambers there-
of with each other. Fig. 3 is a similar view
50 illustrating the manner of closing the open-
ing formed in one of the contiguous vertical
walls of the hub portion, and Fig. 4 is a cross-
sectional view taken on the line *x x* of Fig. 3.

55 Referring to the drawing, *a* is a car-wheel
the rim *a'*, flange *a''*, as well as the spokes *a''*,
of which are of the usual well-known con-
struction. The hub portion, however, form-

ing the subject-matter of my present invention consists of a hollow integral body *b*, com-
posed of three vertical walls *b'*, *b''*, and *b'''* and
two annular walls *b⁴* and *b⁵*. These walls 60
form three chambers *b⁶*, *b⁷*, and *b⁸*, of which
the chamber *b⁶* is connected with the annular
chamber *b⁷* by means of a curved slot *b⁹*, cast
through the annular partition-wall *b⁵*. The
inner annular chamber *b⁸* serves to receive a 65
car-axle, (not shown,) which by filling this
chamber closes the communication of the
chamber *b⁸* with the chamber *b⁶*, otherwise
established between the same, as shown in
Fig. 1. The chamber *b⁸*, which by means of 70
an opening *b¹⁰*, cast into the vertical wall *b'*,
communicates with the exterior of the hub *b*,
is adapted to receive a lubricant, such as oil,
which is introduced into the same through
the opening *b¹⁰*. When the central chamber 75
b⁸, however, is filled by an axle, (not shown,)
the oil in the receiving-chamber *b⁶* is pre-
vented from entering the outer annular cham-
ber *b⁷* and from thence through the slot *b⁹* into
the inner annular chamber *b⁸*, rendering a 80
hub so formed impermeable. In order to per-
mit of the flow of the oil from the receiving-
chamber *b⁶* into the annular distributing-
chamber *b⁷*, the outer vertical wall *b'* and in-
ner vertical wall *b'''*, forming a partition-wall 85
between the chambers *b⁶* and *b⁷*, are pierced
by a drill or other suitable tool, and prefer-
ably three openings *c* and *c'* in the walls *b'*
and *b'''* are formed, of which the openings *c'*
in the partition-wall *b''* are preferably ar- 90
ranged adjacent to the periphery of the in-
terior walls of the chamber *b⁶*, as shown in Fig.
2. These openings *c'* are preferably inclined,
so as to permit of the exit of all the lubricant
introduced into the chamber *b⁶* into the dis- 95
tributing-chamber *b⁷*, which is of larger di-
ameter than the chamber *b⁶*. In order to
permit of the filling of the receiving-chamber
b⁶ up to the central opening *b¹⁰*, the openings
c in the outer wall *b'* are closed by plugs *d* in 100
the manner shown in Fig. 3. These plugs *d*
by tightly fitting the openings *c* render the
partition-wall *b'* liquid-proof, and thus per-
mit of the filling of the receiving-chamber *b⁶*
close to the opening *b¹⁰*. 105

Having thus described the nature and ob-
jects of my invention, what I claim as new,
and desire to secure by Letters Patent, is—

1. The mode of forming a self-lubricating
car-wheel which consists in first forming a 110
wheel having a hollow hub portion composed
of vertical and horizontal walls integral with

each other and dividing the hub into two annular communicating chambers and a single chamber arranged at a right angle thereto, then forming openings in one of the outer and 5 in the intermediate of said vertical walls of the hub so as to connect said single chamber with the outer of said annular chambers, then closing the openings formed in one of the outer walls so as to render the same liquid-proof 10 up to a central opening cast therein, to permit of the filling of the single chamber with a lubricant up to the central opening, and of the flow of the lubricant from the single chamber into the outer annular chamber and from 15 thence into the inner annular chamber of the hub when the wheel occupies an operative or vertical position.

2. The mode of forming a self-lubricating car-wheel, which consists in first casting a 20 wheel having a hollow hub portion, composed of three vertical and two horizontal walls, dividing the hub into two annular chambers connected with each other by an annular opening formed in one of said horizontal 25 walls separating said chambers from each other, and into a single chamber arranged at

a right angle thereto and communicating with one end of the inner annular chamber, and with the exterior of the hub by an opening formed in one of the vertical walls and 30 centrally to said inner annular chamber, then drilling holes through said outer perforated vertical wall and through the intermediate of said vertical walls so as to connect said outer annular chamber with said single chamber, then plugging the holes formed in the outer perforated vertical wall to close the openings drilled therein, to form a chamber capable of receiving a lubricant up to said central opening and to permit the same to 40 flow into said outer annular chamber and from thence by said annular opening into said inner annular chamber or an axle placed therein when the wheel occupies a vertical or operative position.

In testimony whereof I have hereunto set my signature in the presence of two subscribing witnesses.

JAMES W. FULLER, JR.
